UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,146, dated March 6, 1888.

Application filed January 26, 1888. Serial No. 262,071. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

The main feature of my design is the large group of flower and leaf and scroll forms shown at the center of the photograph. The flower forms are circular in general shape. The leaf forms are diversified in character. From cer- 20

tain parts of the group long slender pointed leaves project. The scroll forms are prominently marked, some being open, others being solid with indented or scalloped edges. Above this group and partly separated from it are 25 stems supporting broad leaves. Below the central group is a stem-and-leaf work of a smaller character with some ornamental scroll forms occurring in connection with it. There is a small cluster of leaves and stems with a central flower at one side of the larger group. 30

What I claim as new, and desire to secure by Letters Patent, is—

The design for carpets, consisting of the design substantially as shown.

JAS. L. FOLSOM.
